DESIGN FOR A DRESS

Philip Schlessel, New York, N. Y.

Application October 8, 1937, Serial No. 72,054

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the back opening dress disclosed of contrastingly colored sleeve bands in association with the specific waist yoke and stitching on the rear blouse as shown.

I claim:

The ornamental design for a dress, substantially as shown and described.

PHILIP SCHLESSEL.
